US00D824895S

(12) **United States Design Patent** (10) Patent No.: **US D824,895 S**
(45) Date of Patent: ** Aug. 7, 2018

(54) **COMPUTER**

(71) Applicant: **HEWLETT-PACKARD DEVELOPMENT COMPANY, L.P.**, Houston, TX (US)

(72) Inventors: **Matthew W. Tivnon**, Houston, TX (US); **Binh T. Truong**, Houston, TX (US); **James McClellan**, Houston, TX (US); **Marcus Hoggarth**, London (GB); **Jack Godfrey Wood**, London (GB); **Oliver Poyntz**, London (GB); **Ian Guy**, London (GB); **Isaac Teece**, London (GB); **Stephen De Saulles**, London (GB)

(73) Assignee: **Hewlett-Packard Development Company, L.P.**, Houston, TX (US)

(**) Term: **15 Years**

(21) Appl. No.: **29/609,352**

(22) Filed: **Jun. 29, 2017**

(51) LOC (11) Cl. **14-02**

(52) U.S. Cl.

CLAIM

We claim the ornamental design for a computer, as shown and described.

DESCRIPTION

FIG. 1 is a top, front, right perspective view of the claimed design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines formed by evenly spaced dashes show unclaimed subject matter and form no part of the claimed design. The dot-dash broken lines represent unclaimed boundaries that form no part of the claimed design.

1 Claim, 6 Drawing Sheets
